UNITED STATES PATENT OFFICE.

JULIUS M. FOOTE, OF NEWARK, NEW JERSEY.

DESIGN FOR A CARRIAGE-STEP.

SPECIFICATION forming part of Design No. 16,138, dated June 30, 1885.

Application filed October 20, 1884. Term of patent 7 years.

To all whom it may concern:

Be it known that I, JULIUS M. FOOTE, of the city of Newark, in the county of Essex and State of New Jersey, and a citizen of the 5 United States of America, have invented a new, useful, and original Design for a Carriage-Step as an article of manufacture, of which the following is a specification, reference being had to the accompanying drawings, forming part of the same, in which—

Figure 1 is a plan or face view of a carriage-step containing my invention. Fig. 2 is a section of the same on line $z z$, Fig. 1; and Fig. 3 is a perspective view of the same, together with the arm or bar by which it may 15 be attached to a carriage.

The leading feature of my design for a carriage-step consists in a border of raised pointed projections upon the upper surface of the 20 step, surrounding a center having a plain surface.

A is the step, and B the shank or arm by

which it is attached to the carriage-body. On the upper face of the step is formed a border composed of several lines of fine-pointed pyramidal projections, a , which bound a space or rectangular portion of the said step having a plain surface. Said points may extend from a sixteenth to an eighth of an inch (more or less) from their bases, the said surface of the 30 step thus fashioned presenting to the eye a pleasing appearance.

What I claim, and desire to secure by Letters Patent, is—

The design for a carriage-step herein described and shown, consisting of the plate A, having a border of pyramidal projections, a , within which is inclosed a rectangular portion of the said plate having a plain surface.

JULIUS M. FOOTE.
